UNITED STATES PATENT OFFICE.

ERNEST WILDHABER, OF ROCHESTER, NEW YORK, ASSIGNOR TO GLEASON WORKS,
OF ROCHESTER, NEW YORK, A CORPORATION OF NEW YORK.

METHOD OF AND MACHINE FOR PRODUCING GEARS.

Application filed June 22, 1925. Serial No. 38,725.

The present invention relates to gears and particularly to gears having angularly disposed non-intersecting axes.

One object of the present invention is to provide a method and a machine for the generation of such gears.

A further object of this invention is to provide a method for generating gears having angularly disposed non-intersecting axes which will be applicable for all ratios, large as well as small.

A further object of the invention is to provide a method and a machine for generating gears of the type mentioned, in which the tool represents a basic helicoidal segment and in which the tool and blank are moved relatively to each other as if the blank were rolling on this basic segment.

Other objects will appear hereinafter from the specification and the claims.

In the drawings:

Figs. 1 and 2 are a plan view and side elevation respectively of a pair of gears produced according to my invention;

Figs. 3 and 4 are corresponding views of a helicoidal segment such as may be employed as a basic member for generating a gear constructed according to my invention;

Fig. 5 is a fragmentary view of a pair of helicoidal segments forming the basic members of conjugate gears constructed according to this invention;

Figs. 6 and 7 are views illustrating diagrammatically in plan and in side elevation the pitch surfaces of a pair of gears with angularly disposed non-intersecting axes;

Figs. 8 and 9 are a plan view and a side elevation respectively illustrating diagrammatically the mesh of a gear constructed according to my invention and a basic helicoidal segment;

Fig. 10 is a view illustrating diagrammatically another aspect of my invention with particular relation to the method employed in producing the new gears;

Fig. 11 is a fragmentary side elevation showing a pair of curved tooth gears produced according to this invention;

Fig. 12 is a fragmentary sectional view showing a pair of tools such as might be employed in producing the gears of Fig. 11;

Fig. 13 is a side elevation, partly in section, showing a pair of grinding wheels such as might be employed in producing

curved tooth gears according to this invention;

Fig. 14 is a diagrammatic view showing one of said grinding wheels in relation to the basic segment it represents;

Figs. 15 and 16 are a plan view and side elevation respectively illustrating diagrammatically the method of determining the proportions of certain ratio gears constructed according to this invention;

Fig. 17 is a diagrammatic view illustrating a method of proportioning gears according to this invention where the tooth contact is outside the pitch surface;

Fig. 18 is a plan view showing diagrammatically certain features of the type of gears last referred to;

Figs. 19 and 20 are a plan view and side elevation respectively showing somewhat diagrammatically a machine for producing gears according to this invention;

Gears with angularly disposed non-intersecting axes have the advantage over gears whose axes intersect that the driving member of the pair may be made of any size without altering the gear ratio. This permits of constructing gears with non-intersecting axes in which the driving member is stronger than for equal ratios where the axes are intersecting. Arcuate gears of the type where the axes are non-intersecting have heretofore been produced largely by an operation in which one of the gears, usually the larger member of the pair was given a tooth shape of constant profile, that is, was formed according to a process in which no rolling motion was employed, and in which the smaller member was produced by rolling the blank relatively to a tool which represented a tooth of the formed gear.

The present invention aims to produce both members of the pair according to a rolling or generating process. This method, it is believed, will produce gears which are quieter in operation and of more satisfactory construction than gears produced according to the methods heretofore employed.

One difficulty experienced in the generation of both members of a pair of gears arranged with axes angularly disposed and non-intersecting has been the inability to secure a theoretically correct basic member which might be employed in providing the movements necessary to generate gears of the

type referred to regardless of ratio. In bevel gears and spur gears, a pair of gears will correctly mesh together with full line contact when they are capable of meshing with complementary basic members. These basic members are racks for spur gears and crown gears for bevel gears and frequently these basic members are identical. The present invention has as its basis the provision of a basic member, comparable to the crown gear in bevel gearing and the rack in spur gearing, from which the tooth structure of gears with non-intersecting axes may be derived and from which the proportions of such gears regardless of ratio may be determined.

Figs. 1 and 2 show a pair of gears 9 and 10 having their axes 11 and 12 angularly disposed and non-intersecting. The relative motion of gears of this type, as is well known, can be considered in any instant as a turning motion about an instantaneous axis 13 and a simultaneous translation along said axis 13. The pitch surfaces of such gears are hyperboloids of revolution, being produced by the movement of the instantaneous axis 13 about the respective axes 11 and 12 of the gears. The pitch surfaces will contact along the line 13.

Aside from the gear 9 there exists an infinite number of other gears which may mesh with a gear 10 in such a way that the line 13 is the instantaneous axis. The pitch hyperboloids of all these gears will contact with the pitch hyperboloid of the gear 10 along the line 13 and at any instant the relative motion of the contacting gears may be considered as a combined sliding and rolling motion about and in the direction of the axis 13. In no case will the ratio of relative sliding and turning be the same for the different gears which may mesh with the gear 10. The instantaneous relative motion between the gears is therefore, a helicoidal motion having a different advance or lead for every gear combination of which the gear 9 or 10 is a member and which has an instantaneous axis 13. The tooth contact between a third gear and the gear 10 will depend, therefore, not merely on the location of the instantaneous axis but also on the lead or the advance per revolution of the instantaneous motion.

A consideration of the above facts has resulted in the conclusion that a third member may be interposed between two gears, such as 9 and 10, which will contact either gear along the same lines, if this third member is given not only a rotary motion, but also a translatory motion in the direction of its axis. Such a third member may be made the basic member for the production of gears with non-intersecting axes, which are theoretically accurate and which mesh with line contact.

Such a third member is designated at 14 in Figs. 1 and 2. This third member has an axis 15 which, in the illustrated case of hyperboloidal miter gears, is preferably disposed at right angles to the instantaneous axis 13. This third member will have a helicoidal surface which not only contacts with the pitch surfaces 16 and 17 of the gears 9 and 10 along the line 13, but also the instantaneous relative motion of this third member with respect to either gear 9 or 10 is identical with the relative motion between these two gears, as will be more fully explained hereafter.

A third member of the considered type is illustrated in Figs. 3 and 4. The tooth surface 19 of this member 20 may be represented by a suitable tool, such as the reciprocating tool 21, indicated in dotted lines in Fig. 3 and in full lines Fig. 4. A gear may be accurately generated if the blank is given a motion relative to the tool as of rolling on the basic segment represented by the tool. This relative motion will be composed not only of rotation, as in the case of bevel gears, but also of translation in the direction of the axis 22 of the basic member corresponding to the lead of the pitch surface 23 of said member.

I shall now deduct the relations and formulas which determine the shape of a basic member, such as the member 20, its lead and its position relative to a blank to be operated upon. Referring to Figs. 6 and 7, 24 and 25 are the axes of a pair of gears 26 and 27 having hyperboloidal pitch surfaces. These gears contact along the line 28 which is the instantaneous axis. The angles a' and a'' included between the instantaneous axis 28 and the axes 24 and 25 are determined in known manner by the ratio:

$$\frac{\sin a'}{\sin a''} = \frac{N'}{N''} \quad (1)$$

where N' and N'' are the tooth numbers of the respective gears. The distances z' and z'' of the respective axes of the gears from the instantaneous axis 28 are in the relation:

$$\frac{z'}{z''} = \frac{\tan a'}{\tan a''}. \quad (2)$$

When the axes 24 and 25 are at right angles, $a' + a'' = 90^\circ$, $\sin a'' = \cos a'$ and

$$\tan a'' = \frac{1}{\tan a'}$$

The above formulas will become:

$$\tan a' = \frac{N'}{N''} \quad (1)$$

$$\frac{z'}{z''} = \tan^2 a' \quad (2)$$

In terms of C , the distance between the axes

of the two gears, which distance is equal to $z' + z''$, formula (2^a) becomes:

$$z' = C \sin^2 a' \text{ or } z'' = C \cos^2 a'$$

5 The pitch hyperboloids 26 and 27, which, as stated, may be considered the pitch surfaces of a pair of gears when rotated about their respective axes 24 and 25, in the inverse ratio of the tooth numbers N' and N'' of the 10 gears, will roll on each other and in addition slide in the direction of their contact line 28. At any instant the relative motion between the gears is therefore, a helicoidal motion about the axis 28. The lead of this 15 motion or advance per revolution can be determined as follows:

$$L = 2\pi z' \tan a'' = 2\pi z'' \tan a' \quad (3)$$

When the axes 24 and 25 are at right angles:

$$L = 2\pi \frac{z'}{\tan a'} = 2\pi \frac{z''}{\tan a''} \quad (3)$$

A helicoidal member 29, shown diagrammatically in Figs. 8 and 9, can be constructed

so that its pitch surface will contact with 25 the pitch surface 26 of a gear having an axis 24, such as the gear of Figs. 6 and 7 along the instantaneous axis 28 and so that at any instant the relative motion between the pitch 30 surface of the helicoidal member 29 and the pitch surface 26 of the gear is identical with the relative motion between the pitch surfaces 26 and 27 of the gears shown in Figs. 6 and 7. In other words the relative motion between 35 the helicoidal member 29 and the gear whose pitch surface is represented at 26 must be, at any instant, a helicoidal motion about the instantaneous axis 28, with a lead L as given by formula 3.

The structure and position of the helicoidal member 29 can now be determined. Let 40 L° be the lead of the helicoidal member, z° the distance of its axis 30 from the instantaneous axis 28, and a° the angle between its axis 30 and the instantaneous axis 28, see 45 Figs. 8 and 9. With the known methods of kinematics the following formulas can be derived:

$$z^\circ = \sin^2 a^\circ \left[(z'' - z') + \frac{\tan a'}{\tan a''} \left(z'' + \frac{z'}{\tan^2 a'} \right) \right] \quad (4)$$

and

$$L^\circ = 2\pi \left[\frac{z'}{\tan a'} - \frac{z^\circ}{\tan a^\circ} \right]. \quad (5)$$

z° will be negative when it is within the instantaneous axis, as shown in Fig. 9, and will be

55 positive when it extends beyond that axis. Usually the axes of a pair of gears are disposed at right angles as shown in Figs. 1 and 2. The formula 4 under these conditions become:

$$z^\circ = \sin^2 a^\circ \left[(z'' - z') + \frac{2z'}{\tan a' \tan a''} \right] \quad (4)$$

while formula 5 remains the same. From these formulas it follows, than an infinite 65 number of helicoidal members exist which can mesh with a gear of the type referred to and which possess a relative motion of a type identical to that of the gear. Any one of these members may be employed, 70 therefore, as a basic member from which the gear may be derived. It also follows that a gear having a pitch surface 26 capable of meshing with a third member 29, can mesh with a gear having a pitch surface 27 which 75 itself is capable of meshing with a third member complementary to the member 29. The relationship of these complementary helicoidal members is shown in Fig. 5. They have the same axis 30 and the teeth of one 80 member 29 will fit and completely fill the tooth spaces of the other member 31.

If, from the infinite number of helicoidal members which can mesh with a gear of the type referred to, one is chosen whose axis is

85 at right angles to the instantaneous axis, formulas (4) and (5) become:

$$z^\circ = z'' - z' \quad (4)$$

$$L^\circ = 2\frac{z'}{\tan a'} \quad (5)$$

The hand of the helicoidal third member, which is right hand in Figs. 1 and 2, depends on the relative position of a pair of gears and may be considered in formula (5) by introducing positive and negative signs. The 95 data of a basic member having been determined, a pair of generated gears can be readily produced.

Any tooth form may be adopted for the 100 basic gear, and the teeth do not have to extend necessarily along the instantaneous axis 28, nor is it necessary that they extend along straight lines. The teeth can be longitudinally curved as in the pair of gears, 32, 33, 105 shown in Fig. 11. The only restriction upon the structure of gears produced according to this invention is that the direction of the teeth be such as to permit the relative sliding inherent in this type of gear. By selecting a point on the pitch surface of one 110 of the gears and resolving its velocity by vector analysis, one can determine whether the teeth will permit relative sliding between the pair or not.

At ratios of 1:1 or closely approximating 115 1:1, I preferably use equal addenda on both gears of a pair. At large ratios I preferably increase the diameter of the pinion considerably and provide teeth which are wholly outside of the pitch surface, since hypoid gears, 120

unlike bevel gears, are not restricted to teeth located near the pitch surfaces.

Figs. 15 to 18 illustrate one method of dimensioning a pair of hypoid gears of a ratio other than 1:1. Here the axis 35 of the helicoidal basic member 36 has been assumed at right angles to the instantaneous axis 37. The basic segment here considered is of a form such as shown in Figs. 3 and 4 containing teeth which extend in a radial direction of the axis of the basic segment, being substantially at right angles to said axis. For ratios other than 1:1, where the axis of the basic member is at right angles to the instantaneous axis, if the teeth of the mating gears are so constructed as to lie within the pitch surface, the pinion or smaller member of the pair will be comparatively weak and one advantage of hypoid gears over other drives will thus be lost. By constructing the gears so that their teeth lie outside of the pitch hyperboloids, however, the requisite strength in the driving member may be secured. Under the conditions assumed the distance z^o of axis 35 from the instantaneous axis 37 can be determined from formula (4^b) and lead of the basic member can be determined from formula (5^b).

As previously stated one requirement of a pair of hypoid gears is that they be capable of relatively sliding while in mesh. The direction of relative sliding will always be at an angle to the direction of the instantaneous axis in points outside the pitch surface. Hence the teeth of the pair of gears whose pitch surfaces are indicated at 38 and 39 may be assumed as extending in a direction at an angle e to the instantaneous axis. 40 and 41 are the axes of the two gears whose pitch surfaces are indicated at 38 and 39. 42 indicates the general direction of the teeth, which can also be considered as the radial path of a cutting tool representing the basic segment shown in Figs. 3 and 4. The line 42 extends radially of the axis 35 of the basic member.

Our problem is now to determine the location of the line 42, indicating the general direction of the teeth of the gears, relative to the instantaneous axis. The line 42 comes closest to the instantaneous axis 37 at the point 43, both lines 42 and 37 being parallel to the drawing plane of Fig. 17. The point 43 will preferably be so chosen as to be about midway of the face of the gear. The direction of relative sliding at any one point equals the direction of the tangent to a helix whose axis coincides with the instantaneous axis 37 and whose lead L is determined by equation (3). The direction of relative sliding at the point 43 coincides with the direction 42 of the teeth, when the distance of the line 42 from the instantaneous axis 37 is such that the line 42 is a tangent to the helix just mentioned at the point 43. The

distance of the line 42 from the instantaneous axis 37 is indicated by d in Fig. 18. This distance d evidently depends on the angle e shown in Fig. 17. d hence may be determined by:

$$d = \tan e \cdot \frac{z'}{\tan a'}$$

From the above the dimensions of a pair where the teeth lie outside the pitch surfaces may be determined. The cone angles of the blanks can be determined from their relationship to a tangential plane 45, tangent to the auxiliary conical surfaces 46 and 47 of the pair at a point 43. In case of large reductions, I preferably provide pairs whose cone angles are in predetermined relation to the longitudinal curvature of the teeth. These pairs may be proportioned according to the principles disclosed in my copending application, Serial No. 29,553 filed May 11, 1925.

The teeth of the basic member, as previously stated may be either curved or straight. In either case, however, as already described, the teeth of this basic member will be of constant profile and will preferably be constantly inclined, that is, will make a constant angle, with respect to the axis of said member. Where the teeth of this member are straight, as shown in Figs. 3 and 4, the side surfaces of the teeth will be planes; where the teeth are curved, the sides will preferably be made surfaces of revolution.

Gears capable of meshing with a basic segment whose teeth are straight may be produced by reciprocating a tool, representing one or both sides of the teeth across the face of a gear blank while imparting an additional relative movement between the tool and blank as if the basic segment were meshing with the gear to be produced from the blank. This relative movement will consist of a rotation of the blank and segment, represented by the tool, on their axes in timed relation and a relative translation in a direction of the axis of the basic segment. The tool may be reciprocated toward the axis of the basic segment or may be offset therefrom. One gear of a pair will be produced by a tool representing one segment and the other gear will be produced by a tool representing a complementary segment. The cutting edges of the tools may be straight or curved.

Fig. 12 shows a pair of rotary tools 48 and 49 of the face mill type such as might be employed for producing gears conjugate to complementary basic segments having longitudinally curved teeth. The coinciding axes of the basic segments are indicated at 50 and their pitch surfaces at 51.

Fig. 13 shows a pair of grinding wheels 52 and 53, having grinding surfaces 54, 55, and 56, 57, which are portions of spherical

surfaces, representing a basic member whose teeth have side surfaces which are portions of spherical surfaces. The adjacent tooth sides of the basic segment 20^a are parts of 5 convex and concave spherical surfaces respectively, which may have equal radii 58 and 59. Adjacent tooth surfaces have centers 60, 61, 62, 63, 64 and 65 located in two helices 66 and 67. The centers of the convex surfaces of the segment represented by 10 the wheel 52 are located on the helix 66, while those of the concave surfaces are located on the helix 67.

The two adjacent spherical sides of a 15 tooth of the basic member may be represented by a wheel 52 when its axis 68 passes through the centers 63 and 64 of the tooth sides. The two adjacent spherical sides of the complementary basic member may be 20 represented by the wheel 53 when its axis 69 passes through the centers 64, 65 of the tooth sides. In this way a pair of male tools may be employed to produce conjugate gears, and with such tools it is possible to 25 produce teeth of changing depth.

In certain cases for the sake of structural advantages in machines employed for practicing this invention, a slight departure from theoretical requirements is possible. Fig. 30 10 illustrates the use of tools 70 and 71 representing basic segments 72 and 73 which are not strictly complementary. The segments have teeth arranged on helicoidal surfaces 74 and 75. The departure from strict 35 theory in this case is analogous to the structural departures often made in bevel gear cutting machines.

One form of machine for practising this invention is shown in Figs. 19 and 20. In 40 the embodiment illustrated, reciprocating tools 76 and 77 are employed representing the adjacent tooth sides of a basic segment whose teeth are straight and whose side surfaces are planes. The tools 76 and 77 are 45 reciprocated along lines 78 and 79 in such manner that the points of the cutting edges of the tools move in parallel planes, whereby the tools represent the teeth of the basic segment. The blank 80 is rotated about its 50 axis 81 while in engagement with the tools. The tools are mounted on a cradle or support 82 which is journaled in a circular bearing 83 of the frame 84 of the machine.

The tools, as already indicated, are moving 55 relative to the support 82, their cutting edges being maintained at a constant inclination to a plane perpendicular to the axis 85 of the cradle, which axis represents the axis of the basic helicoidal segment. The 60 blank spindle 86 is rotatably mounted on a slide 87 which can be adjusted vertically on the upright 88 which is itself angularly adjustable on the table or carrier 89. The carrier 89 is adjustable and movable in a direction 65 parallel to the axis 85 of the cradle 82.

During generation, the rotation of the cradle, indicated by the arrow 90, the rotation of the blank indicated by the arrow 91 and the feeding movement of the table or carrier 89, indicated by the arrow 92 are so 70 timed that their movements impart to the tool and blank a relative motion as of a gear rolling on the basic helicoidal segment represented by the tools. The direction of feed of the table may be either toward or 75 from the cradle, depending on the direction of rotation of the blank and cradle.

Gearing for imparting the required motion to the various parts is indicated 80 diagrammatically. The shaft 93 drives the worm 94 through a pair of miter gears 95, a shaft 96, and a second pair of miter gears 97. The worm 94 meshes with a worm wheel 98 secured to the cradle 82 and imparting motion thereto. The blank spindle 86 is driven from the shaft 93 by means of a miter gear 99, which is splined to the shaft 93, and which is journaled in a part 100 connected with the carrier 89. The miter gear 99 meshes with a miter gear 101 secured to a shaft 102, which drives a shaft 103 through change gears 104. The shaft 103 has keyed to it a worm 105 meshing with a worm wheel 106 secured to the blank spindle 86. The blank carrier 89 is moved on the frame 84 by means of a screw 109 which is driven from the shaft 93 by means of change gears 107. The screw 109 engages a nut 108 which is secured to a carrier 89. 95

In operation the tools are reciprocated 100 across the face of the blank, while the blank rotates on its axis and while the cradle slowly moves about its axis and the blank carrier is given a movement in a direction parallel to the cradle axis. These three 105 motions are in timed relation and generate the tooth profiles. When the cradle has been so turned that the tools 76 and 77 have been fed past the blank, two tooth sides of the blank will have been completed. The generating 110 movements will then be reversed and the blank withdrawn and indexed. The cycle will then commence anew. For the sake of clearness the indexing mechanism has been omitted as well as the mechanism for clapping the tools out of position on their return strokes across the face of the blank. It will be understood, however, that any suitable indexing mechanism may be employed 115 and any suitable clapping means. It will be understood, also, that instead of intermittently indexing the blank, the blank may be continuously indexed as in a hobbing operation. 120

The operation of the machine remains in 125 principle the same, when instead of planing tools a face mill such as shown in Figs. 12, 13 and 14 is employed. This face mill will be rotated about its axis, while the relative generating movements remain the same as in 130

the machine already described. As in the case of the reciprocating tools, the points of the cutting edge of the face mill will move along lines lying in parallel planes, that is to say the cutting edge will move along a line of constant curvature, representing a tooth side of the basic segment.

While I have illustrated one embodiment of a machine for practising the invention, it will be understood that various other types of machines may be employed. In general, the methods employed for the cutting of bevel gears may be applied to the cutting of the hypoid gears described when so modified as to allow for the helicoidal nature of the basic segments.

While I have illustrated my invention particularly with reference to hypoid gears having tapered bodies, it is obvious that my invention also relates to other forms of gears with non-intersecting axes, as worm gears.

Gears which are derived from a basic tooth surface which is a plane or a surface of revolution can be readily ground and this invention is to be understood as including grinding as well as cutting.

In general, while I have illustrated and described a preferred embodiment of the invention, it will be understood that the invention is capable of further modification within the limits of the disclosure and the scope of the appended claims. This application is intended to cover any variations, uses, or adaptations of my invention, following, in general, the principles of the invention and including such departures from the present disclosure as come within known or customary practice in the gear art and may be applied to the essential features hereinbefore set forth and as fall within the limits of the appended claims.

Having thus described my invention, what I claim is:

1. The method of producing gears which consists in moving a tool across the face of a gear blank while imparting an additional relative movement between the tool and blank as of a gear rolling on a helicoidal segment provided with teeth of constant profile and constantly inclined with respect to its axis.

2. The method of producing gears which consists in moving a tool across the face of a gear blank while imparting an additional relative movement between the tool and blank as of a gear rolling on a helicoidal segment provided with teeth whose side surfaces are planes.

3. The method of producing gears which consists in moving a tool across the face of a gear blank so that points of its cutting edge move along lines lying in parallel planes, rotating the blank about its axis while in engagement with the tool and im-

parting a relative helicoidal movement between the tool and blank about an axis offset from the blank axis.

4. The method of producing gears which consists in moving a tool across the face of a gear blank so that points of its cutting edge move along lines lying in parallel planes, rotating the blank on its axis while in engagement with the tool and imparting an additional relative movement between the tool and blank about an axis offset from the blank axis in timed relation with the blank rotation and simultaneously feeding the blank and tool relatively to each other in a direction parallel to the axis about which the last named movement takes place.

5. The method of producing gears which consists in moving a tool across the face of a gear blank so that points of its cutting edge move along lines lying in parallel planes, rotating the blank on its axis while in engagement with the tool and imparting an additional relative movement between the tool and blank about an axis offset from the blank axis and simultaneously feeding the blank and tool relatively to each other in a direction at an angle to the axis of rotation of the blank.

6. The method of producing gears adapted to mesh interchangeably with a basic helicoidal segment which consists in moving a tool across the face of a gear blank so that points in its cutting edge move along lines lying in parallel planes, while imparting an additional relative movement between tool and blank as of a gear rolling on said basic segment.

7. The method of producing gears which consists in moving a tool across the face of a gear blank, rotating the blank on its axis and imparting a relative helicoidal movement between the tool and blank about an axis offset from the axis of the blank while maintaining the cutting edge of the tool at a constant inclination to a plane perpendicular to said last named axis.

8. The method of producing gears which consists in moving a tool in a straight line across the face of a gear blank, rotating the blank on its axis and imparting an additional relative movement between the tool and blank about an axis offset from the axis of the blank while maintaining the cutting edge of the tool at a constant inclination to a plane perpendicular to said last named axis and feeding the tool and blank relatively to each other in a direction parallel to said last named axis.

9. The method of producing gears which consists in moving a tool across the face of a gear blank rotating the blank on its axis while in engagement with the tool and simultaneously moving the tool about an axis offset from the axis of the blank in timed

relation to the blank rotation while imparting a relative feeding movement between tool and blank in a direction parallel to the last named axis.

6 10. The method of completely generating a gear which consists in moving a tool across the face of a gear blank, while rotating the blank on its axis, simultaneously imparting an additional relative movement between the tool and blank about an axis offset 70 from the blank axis and feeding the tool and blank relatively to each other in a direction at an angle to the blank axis.

10 11. The method of producing gears which 15 consists in moving a tool across the face of a gear blank, rotating the blank on its axis while in engagement with the tool, moving the tool at a constant rate about an axis offset from the axis of the blank and simultaneously 20 feeding the tool and blank relatively to each other in a direction parallel to the last named axis.

12. In a machine for producing gears, a tool, means for moving the tool across the 25 face of a gear blank so that points of its cutting edge move along lines lying in parallel planes, means for rotating the blank on its axis while in engagement with the tool and means for simultaneously imparting 30 an additional relative movement between the tool and blank about an axis offset from the blank axis.

13. In a machine for producing gears, a tool, means for moving the tool across the 35 face of a gear blank so that points of its cutting edge move along lines lying in parallel planes, means for rotating the blank on its axis while in engagement with the tool and means for simultaneously imparting an 40 additional relative movement between the tool and blank about an axis offset from the blank axis in timed relation with the blank rotation.

14. In a machine for producing gears, a tool, means for moving the tool across the 45 face of a gear blank so that points of its cutting edge move along lines lying in parallel planes, means for rotating the blank on its axis while in engagement with the tool and means for simultaneously imparting an 50 additional relative movement between the tool and blank about an axis offset from the blank axis and means for imparting a relative feeding movement between the tool and blank in a direction parallel to the axis about 55 which the last named movement takes place.

15. In a machine for producing gears, a tool, means for moving the tool across the face of a gear blank and means for imparting an additional relative movement between the tool and blank as of a gear rolling on a helicoidal segment provided with teeth of constant profile whose side surfaces are constantly inclined with respect to the 60 axis of said segment.

16. In a machine for producing gears adapted to mesh interchangeably with a basic helicoidal segment, a tool, a support for a gear blank, means for moving the tool across the face of the blank so that points of its cutting edge move along lines lying in parallel planes and means for imparting an additional relative movement between the tool and blank as of a gear rolling on said 75 basic segment.

17. In a machine for producing gears, a tool, means for moving the tool across the face of a gear blank, means for rotating the blank on its axis while in engagement with the tool and means for simultaneously moving the tool about an axis offset from the blank axis in timed relation with the blank 80 rotation.

18. In a machine for producing gears, a tool, a support for a gear blank rotatable on an axis coinciding with the axis of the blank, means for moving the tool across the face of the gear blank, means for rotating the blank support, means for simultaneously moving the tool about an axis offset from the axis of the blank in timed relation with the blank rotation and means for simultaneously imparting a relative feeding movement between the tool and blank support in a direction at an angle to the axis of the 95 blank.

19. In a machine for producing gears, a frame provided with a circular bearing, a tool support journaled in said bearing, a tool mounted on said support for movement relative to said support, a blank carrier slidably mounted on the frame, a blank spindle rotatably mounted on the carrier, means for moving the tool across the face of the blank mounted on said spindle and means for simultaneously and in timed relation moving the tool support in its bearing, rotating the blank spindle on its axis, and moving the blank carrier on the frame.

20. In a machine for producing gears, a frame, a support oscillatably mounted on the frame, a support slidably mounted on the frame, said last named support being movable in a direction parallel to the axis of oscillation of said first named support, a tool mounted on one of said supports for movement independently thereof, a blank spindle rotatably mounted on the other of said supports, means for moving the tool relative to its support across the face of the blank and means for simultaneously and in timed relation rotating the blank spindle on its axis and imparting to said supports their respective movements relative to the frame.

21. In a machine for producing gears, a frame, a tool support rotatably mounted on said frame, a blank carrier slidably mounted on said frame, a tool mounted on said tool support for movement relative thereto, a blank spindle journaled in said blank sup-

- port having an axis of rotation coinciding with the axis of the blank carried thereby and offset from the axis of rotation of the tool support, means for moving the tool relatively to its support across the face of the gear blank, means for rotating the blank spindle on its axis and means for simultaneously and in timed relation therewith moving the tool support about its axis and actuating the blank carrier on the frame.
22. The method of producing a gear which consists in moving a tool across the face of a gear blank while imparting a relative rolling movement between the tool and blank in the manner of a gear rolling on a helicoidal segment whose side tooth surfaces are of constant profile and such as might be generated by a line, the points of which move in parallel planes.
23. The method of producing a gear which consists in moving a tool across the face of a gear blank while imparting a relative rolling movement between the tool and blank in the manner of a gear rolling on a helicoidal segment whose side tooth surfaces are of straight profile and such as might be generated by a line, the points of which move in parallel planes.
24. The method of producing a gear which consists in moving a tool across the face of a gear blank while imparting a relative rolling movement between the tool and blank in the manner of a gear rolling on a helicoidal segment having teeth which are of constant profile and which extend radially of its axis.
25. In a machine for producing gears, a frame, a tool support, a tool carried thereby, a rotatable blank support, a cradle, journaled in the frame, upon which one of said supports is mounted, means for positioning the blank support with its axis offset from the axis of the cradle, means for moving the tool across the face of the blank, means for imparting a rotary movement to the blank support and for simultaneously imparting movement to the cradle, and means for simultaneously imparting a further relative movement between the tool and blank in a direction parallel to the cradle axis.
26. In a machine for producing gears, a tool, a blank support, means for moving the tool across the face of the blank and means for simultaneously imparting an additional relative movement between the tool and blank in the manner of a gear rolling on a helicoidal segment whose side tooth surfaces are of constant profile and such as might be generated by a line, the points of which move in parallel planes.
27. In a machine for producing gears, a frame, a tool support, a tool carried thereby,
- a rotatable blank support, a carrier, upon which one of said supports is mounted, journaled in said frame, means for positioning the blank support with its axis offset from the axis of said carrier, means for moving the tool across the face of the blank so that points in its cutting edge move in parallel planes, means for rotating the blank support on its axis and means for simultaneously imparting movement to the carrier on its axis.
28. In a machine for producing gears, a frame, a tool support, a tool carried thereby, a rotatable blank support, a carrier, upon which the tool support is mounted, journaled in said frame, means for positioning the blank support with its axis offset from the axis of said carrier, means for moving the tool across the face of the blank, means for rotating the blank support on its axis and means for simultaneously imparting movement to the carrier on its axis.
29. The method of producing a gear which consists in cutting its side tooth surfaces by reciprocating a tool in a straight path across the face of a gear blank, while rotating the blank on its axis and simultaneously imparting a relative rotational movement between the tool and blank about an axis intersecting the tool path and offset from the blank axis and in timed relation therewith, a relative feed movement in the direction of the axis about which the last named movement takes place.
30. In a machine for producing gears, a frame, a support rotatably mounted on the frame, a support slidably mounted on the frame for movement in a direction parallel to the axis of rotation of the first support, a tool mounted on one of said supports for movement radially of the axis of the first support, a blank spindle journaled in the other support, means for positioning the blank spindle with its axis offset from the axis of the first support, means for reciprocating the tool, means for rotating the blank, and means for simultaneously and in timed relation rotating the first support on its axis and feeding the second support in a direction parallel to the last named axis.
31. In a machine for producing gears, a blank spindle, a tool, means for rotating the blank spindle on its axis, means for simultaneously imparting a relative rotational movement between the tool and blank on an axis offset from the blank axis, means for imparting a relative feed movement in the direction of said offset axis, and means for reciprocating the tool across the face of the blank in a line extending radially of said offset axis.

ERNEST WILDHABER.
